CARBURETOR

Don Cole, Chicago, Ill., assignor to Bendix Products Corporation, South Bend, Ind., a corporation of Indiana

Application May 9, 1927, Serial No. 189,983

66 Claims. (Cl. 261—34)

My invention relates to carburetors such as are now employed for the engines of automobiles, and the like, and it is more particularly concerned with the matter of securing the proper fuel feed for acceleration of the engine.

The present tendency in automobile development is to redesign the engine to provide greater power and, particularly, more rapid acceleration of the vehicle for a given weight. There is also a tendency to extend the range of operating speeds of the engine. For securing a greater amount of power and higher speed, a large carbureting opening and intake passageway is desirable, but this affects adversely the ability of the engine to accelerate the vehicle with carburetors now known. A carburetor and its engine must for best results be considered as a unit.

In order to secure maximum horsepower at high speed, it is necessary to use a large size carburetor and intake manifold. Thereby, the horsepower at high speed is materially increased, and the change does not affect to any great extent the wide open throttle performance at low speed, assuming that the engine is running at any given speed with wide open throttle. However, this change greatly impairs the flexibility and acceleration of the engine at low speed, and acceleration becomes the most troublesome problem in the running of the engine. The necessity for an increased size of carburetor and intake passageway is well appreciated by those skilled in the art in that a very low vacuum is desirable in the intake manifold at high speeds in order to provide maximum volumetric efficiency.

This requirement of very low vacuum at wide open throttle on high speed necessitates a large venturi in the plain tube type of carburetor, or a light spring in an expanding type of carburetor. Such a construction automatically permits of the maintenance of a very low vacuum at wide open throttle on low speed, and by the same token it reduces the suction at the fuel nozzle to a minimum. Furthermore, it reduces the suction on the nozzle further when the engine is running at idle speeds with substantially closed throttle.

It is well known that an automobile engine will pull constantly at a very low speed with wide open throttle, but will not respond, assuming the same construction, should the throttle be suddenly opened from a closed or idling position, unless it is aided by some accelerating device which applies an extra amount of fuel to the carburetor to compensate for the tendency of the fuel from the main jet to lag behind the air.

I am aware that it has been proposed heretofore to provide positively operated means for injecting fuel during opening of the carburetor throttle for accelerating the engine, but devices of this character, as known in the prior art, have one fundamental defect in that they do not provide a definite quantity of fuel for a given displacement of the throttle. In prior devices with which I am familiar, an excessive amount of fuel is discharged from the nozzle when it is not needed.

According to my invention, I provide an accelerating mechanism which discharges a given volume of fuel for a given opening of the throttle in such a manner as to meet the requirements of the engine for acceleration more accurately than is provided by devices of the prior art.

In the preferred form of my invention, I provide a pump having a given volumetric discharge for a given change in throttle position independently, or substantially independently, of the rate at which the throttle position is changed. Furthermore, in the preferred form of my invention, repeated rapid operations of the throttle will not flood the carburetor with liquid fuel.

According to my invention the accelerating fuel discharge is prolonged beyond the opening motion of the throttle to which it corresponds. That is to say, the discharge of the accelerating fuel increment is spread over a considerable period of time instead of being dumped into the air stream in a lump. In the preferred form of my invention this is secured by energizing a spring which recoils or deenergizes through an element involving the displacement of liquid from a chamber through a restricted outlet. The spring is energized at the opening of the throttle. Its recoil rate is independent of its energizing rate.

The motion of the opening of the throttle is transmitted to a valve element which opens an auxiliary or supplementary passageway for fuel in addition to the main fuel feed passageway. The timed recoil of the spring closes that valve. During the open position of the valve the auxiliary passageway supplies fuel for accelerating purposes. This fuel may be supplied in either or both of the following ways, first, by suction from the float chamber past said valve, second, by directing the liquid discharged by the spring from said chamber into said supplementary passageway.

The element which provides for such slow displacement of liquid from a chamber is essentially a timing element or a dash-pot, but its discharge

may be utilized for supplying the accelerating charge and then it is at the same time a pump.

The carburetor of my invention provides, in addition to the means for securing extra fuel feed for acceleration purposes, means for compensating the flow of liquid fuel to meet the requirements of the carburetor at wide open throttle. In other words, in addition to the accelerating feature, I provide in conjunction therewith a compensating feature.

Now, in order to acquaint those skilled in the art with the manner of constructing and operating a device embodying my invention, I shall describe in connection with the accompanying drawings a specific embodiment of the same.

In the drawing:

Figure 1 is a diagrammatic sectional view of a carburetor embodying my invention;

Fig. 2 is a horizontal section taken on the line 20 2-2 of Fig. 1;

Fig. 3 is a diagrammatic sectional view of a modification;

Fig. 4 is a like diagrammatic sectional view of another modification;

Fig. 5 is a diagrammatic sectional view of a modified form of pump and valve element;

Fig. 6 is a fragmentary sectional view of a modified form of accelerating compensating device;

Fig. 7 is a diagrammatic sectional view of a further embodiment of the invention; and

Fig. 8 is a diagrammatic sectional view of a further embodiment.

Referring first to the embodiment shown in Figs. 1 and 2, the carburetor comprises essentially a body having certain passageways therethrough and provided with movable parts appurtenant to the passageways. The body 1 has an air inlet at 2 communicating through a constricted Venturi shaped passageway 3 with the outlet opening 4. The outlet opening 4 is surrounded by the usual attaching flange 5 by which the carburetor is supported from the intake manifold of the engine. The outlet 4 is controlled by butterfly throttle valve 6 mounted on a rotating shaft 7 having suitable bearings in bosses formed on the side of the carburetor body. The throttle valve may be of any preferred type.

The carburetor is provided with a liquid fuel chamber 8 which may be integral with or formed separately from the main body 1. The fuel chamber 8 is provided with a cover member 9 secured as by suitable screws 10 over the top of the fuel chamber. A float 11 is hinged at 12 inside the fuel chamber, and this float controls a float valve 13 governing an admission port 14 communicating with a source of liquid fuel through the supply pipe 15. Any other suitable means for regulating the inflow of liquid fuel to the constant level chamber 8, or to hold the level therein substantially constant, may be provided.

The carburetor body is provided with a fuel discharge nozzle 16 terminating within the Venturi constriction 3 slightly above the most restricted part. Obviously, this nozzle may be made integral or as a separate part, as is well known to those skilled in the art. It may comprise a single passage or a plurality of passages. The nozzle 16 contains a vertical passageway 17 communicating at its lower end with a lateral passageway 18, this passageway 18 branching to provide communication through the controllable or regulable port 19 with the constant level chamber 8, and communicating by way of a con-

trollable or regulable constriction 20 with a cylinder or chamber 21. The restriction 20 is formed as a removable plug having a drilled passageway therethrough. By substituting plugs, the size of the restriction may be adjusted. This cylinder or chamber 21 has a passageway 22 leading to the bottom of the float chamber 8, but which passageway 22 is normally closed by valve member 23 on the lower end of a stem or plunger 24. The port 19 is controlled by an adjustable needle valve 25 in a manner known to those skilled in the art.

The vertical fuel passageway 17 communicates intermediate its ends with a horizontal passageway 26 through a controllable restriction 27 with a vertical passageway 28. The passageway 28 leads to the idling discharge opening or nozzle 29 above the throttle, and it has communication with an air inlet opening 30 below the throttle communicating with the space between the nozzle 16 and the throttle valve 6, commonly termed the mixing chamber 31.

The vertical passageway 28 is preferably provided with a restriction at 32 just below the point at which the air inlet 30 joins the vertical passageway.

A second air inlet 33 leading to the outside of the carburetor body is also provided to admit air from the outside, although the opening 33 may be dispensed with upon making proper provision for the entry of air at the opening 30. It is contemplated within the construction shown that these openings 30, 29 and 33 may be adjustable as desired.

The parts of the carburetor thus far described provide for the normal function of introducing a predetermined amount of liquid fuel into the air flow passing into the intake manifold for both idling and for normal running. During idling the throttle valve 6 is closed, or substantially closed, and liquid fuel is drawn up through the vertical passageway 28 from the float chamber and discharged at the restriction 32 into the flow of air which passes in through the opening 30 and into the opening 29, and is discharged at the opening 29 into the intake manifold above the throttle.

Upon opening of the throttle the opening 30 is placed under suction at the same time that air passes around the edges of the throttle, and a greater amount of air and a greater amount of fuel are then supplied to the engine. At the same time, the current of air through the venturi 3 tends to draw liquid fuel from the nozzle 16, so that for further open positions of the throttle 6 fuel may be discharged at both the nozzle 16 and at the constriction 32 in the vertical passageway 28. Upon further open position of the throttle 6 the main discharge of fuel occurs at the nozzle 16 and a reversal of flow through the vertical passageway 28 may occur and air pass down through the constriction 32 and into the passageway 17 to reduce the flow of fuel out of said nozzle 16 and break up the same by the inflow of air.

It will be apparent to those skilled in the art that the nozzle 16 may be air bled by other means than that shown, if so desired.

If the setting of the needle valve 25 is proper for providing a suitable mixture of air and liquid fuel for running at a given speed or speeds, it will be apparent that sudden opening of the throttle 6 will admit to the intake manifold a quantity of air for which there is not a corresponding quantity of liquid fuel due to the friction of flow of the liquid fuel and due to the inertia of the

same. This is particularly aggravated in case the venturi 8 is of ample size to pass sufficient air at wide open throttle position.

As a preferred means for securing a suitable discharge of fuel from the nozzle 16 upon opening of the throttle valve 6, I provide a cam 35 on the throttle shaft 7 for operating a lever 36 pivoted at 37' to the body of the carburetor. The lever 36 at its free end is suitably connected to the rod 37 which extends down through the cover 8 and is connected by a pivotal joint 38 to a plunger 39 which is guided within a cylindrical guide 40. In the form shown in Figs. 1 and 2, the guide 40 is a complete cylinder formed as an integral part of the cover member 8, but obviously this may be varied. The plunger 39 acts like a piston guided in the guide 40, fitting closely within said guide 40 and providing on its interior the chamber or cylinder 41. This chamber has cylindrical walls 20 and forms a cylinder for the piston 42, which piston is connected to the upper end of the hollow stem 24. The stem 24 has a passageway 43 communicating with the interior of the cylinder 41 and having a discharge opening 44 extending out laterally, and when the parts are in the position shown in Figs. 1 and 2, said port opens into the bottom of the float chamber 8. The stem 24 is preferably threaded into the piston 42 and the head 23 of the stem forms a valve normally closing the passageway 22, as previously referred to. The piston 42 bears a pin 45, the length of which is adjusted to engage the head of the cylinder 41 when the same is moved down to a position corresponding to substantially wide open throttle.

35 A spring 46 bearing against the bottom of the piston 42 and the bottom wall of the float chamber 8 tends to close the valve 23 by raising the piston and stem until said valve 23 closes the port 22.

40 The stem 24 preferably has clearance in the port 22 for a purpose later to be described, but it is within the scope of my invention to have the stem 24 fitting closely in said port 22.

45 A spring 47 surrounding the rod 37 tends to raise the lever 36 and connected parts until upward motion is stopped by engagement with the cam 35.

The operation of these parts is as follows:

50 Assume that the parts are in the condition shown, and that the carburetor is supplied with fuel and attached to the engine, the engine may idle with the valve 6 closed, as shown, and when it is desired to accelerate the engine the shaft 7 is turned by any suitable means, as is well known to those skilled in the art, to open the valve 6. Such opening movement rotates the shaft 7 and causes the cam 35 to depress the lever 36, swinging it about its pivot 37', and in turn causing the lever to force the plunger member 39 downwardly, this plunger member containing the cylinder 41. The first result of depressing the plunger 39 is to place the liquid in the chamber 41 under pressure and to tend to expel the same through the passageways 43 and 44. Such downward pressure 55 compresses the spring 46 and causes the discharge opening 44 to be forced below the wall in which the opening 22 is formed, discharging liquid fuel from said port 44 into the chamber 21, and thence through the restriction 20 and into the fuel passageways 18 and 17. At the same time, the depression of the plunger 39 tends to raise the level of liquid in the float chamber slightly. This effect 60 may be controlled by suitable proportioning of the parts to secure an advantageous effect in 65 raising the liquid level, or the said effect may be

minimized to whatever degree desired. Since the liquid cannot immediately leave the chamber 41 when the plunger 39 is depressed, the stem 24 will be carried down into the chamber 21 and the liquid fuel discharged from the opening 44. It is to be observed that the rate of discharge of fuel from said opening 44 and into the feeding passageway 18 is not directly dependent upon the rate of motion of opening of the valve 6, but is dependent upon the force exerted by spring 46. 10 For example, assume that the valve 6 is suddenly thrown to a partially open position. The lever 36 must swing down and the plunger 39 be depressed, since the cam 35 positively moves the lever 36. However, the piston 42 is yieldably held by the 15 spring 46 and it can move downwardly. Hence, upon initial actuation of the lever 36 downwardly, the plunger 24 is projected into the well or cylinder 21, and the spring 46 being thereby compressed raises the piston 42, discharging liquid 20 fuel from the cylinder 41 through the restriction 20 into the fuel passageway 18. Hence, upon initial opening of the throttle, fuel is immediately injected at the same instant that more air is admitted and there is a continuation of discharge 25 after the initial motion which has caused it. This is highly beneficial in two ways; first, a definite quantity of fuel is discharged, depending upon the throttle position independently of the rate at which the throttle is opened; and, second, the 30 time required for the discharge of the predetermined quantity of fuel according to throttle setting is advantageous in preventing successive operations of opening the throttle 6 from flooding the carburetor with additional injections of 35 fuel. This discharge is spread over an appreciable period of time and thereby secures a beneficial effect. The throttle valve 6 may be closed without immediate filling of the chamber 41, since the connection between the shaft 7 and the 40 lever 36 is an impositive and under certain conditions a lost motion connection and successive quick opening and closing of the throttle 6 will not discharge repeated charges of fuel, as in the case of devices of the prior art.

45 There is, therefore, a definite quantity of liquid fuel discharged corresponding to each increase of throttle opening.

The pin 45 previously referred to acts as a stop between the head of the plunger 39 and the piston 42 when the throttle is substantially wide open to open the valve 23 and to permit additional fuel to be drawn through the clearance between the stem 24 and the opening 22, thence through the constriction 20 into the fuel supply passageway 18. There is a tendency at wide open throttle for the air bled jet 16 to thin out the mixture to too great a degree, and a compensating flow of fuel through the constriction 20 into the fuel supply passageway 18 is provided to meet this 55 tendency to form a mixture which is too lean.

It will be observed that the projection of the plunger 24 into the well 21 has a displacing effect, forcing fuel out of said chamber 21 upon the initial movement. Such displacing effect of the plunger 24 may be largely relied upon for the accelerating discharge. In such event, the particular feature of preventing successive operations of the accelerating fuel feed mechanism for successive operations of the throttle valve is secured, 70 even though delayed discharge is, or is not, present.

I have shown in Fig. 3 an embodiment of certain features of my invention. In this case the guide 40 is formed separately from the float

chamber 8. The stem 31, which depresses the plunger 38, is actuated by a bell crank lever 48, one arm of which, as shown at 50, comprises a cam engaging a roller on the upper end of the stem 31 to depress the same. The lever 48 is pivoted on a rocking shaft 51 and is actuated by the same actuating rod 52 which is connected to the operating arm 53 on the throttle shaft 1.

The nozzle 16 has a separate vertical passageway 53. In the present form the passageway 53 is in parallel to the main fuel passageway 11, and is connected to the chamber 21 so that the discharge of fuel for acceleration is distinct from the normal discharge of fuel under suction control from the float chamber. Thus, instead of two branches to a single outlet, there are two passageways having separate outlets into the air stream. This is optional.

The plunger 24' is made of a size to secure a substantial displacement of fuel, as may be required, when the same is thrust down into the chamber 21. The space 81 within the cylindrical guiding chamber 48' below the plunger 38 communicates with the float chamber 8 through a passageway 54 which has sufficient retarding effect on return flow to secure a positive effect below the piston 42, tending to prevent excessive leakage out of the chamber 21 back into the float chamber. The plunger 24' may be made with clearance about the opening 22 which it controls. The delayed effect is secured in the present instance by leakage between the piston 42 and the walls of the cylinder of the plunger 38. That is to say, depression of the plunger 38 causes depression of the displacing plunger 24' to force fuel from the chamber 21 and, at the same time, force some fuel out of the chamber 41 around the piston 42, so that an immediate repetition of opening and closing of the throttle valve 6 tends to be less effective for discharging fuel until sufficient time has elapsed to permit filling of the chamber 41. In this case the dash-pot effect is most prominent. It will also be observed that during the time that the plunger 24' is moving up to where the head or valve 23 closes off the passageway 22, there is a passageway open for fuel to be drawn from the float chamber through the clearance about the plunger 24', through the chamber 21, constriction 26, and out the passageway 53. This, however, is cut off by the valve 23 as soon as the plunger 42 rises under the influence of the spring 46 to a point where the valve 23 closes.

I have shown in Fig. 5 a construction of stem 56 in which a substantial clearance is formed between said stem and the walls of the opening 22, and where it is intended that the opening of said clearance passageway by depression of the plunger 56 to move the valve 23 from the opening 22 shall provide a suction passageway through which fuel may be drawn by suction. That is to say, in this case the stem 56 is of relatively small displacement and has no great effect on displacing liquid from the chamber 21, but it provides by opening the passageway 22 for liquid fuel to be drawn by suction during the time that such valve is open. I have shown these three different forms of plungers to indicate the different functions which are emphasized by each. In the plunger 24, as shown in Fig. 1, the function which is emphasized is the positive discharge from the chamber 41 into the fuel supply passage by upward movement of the piston 42 in the cylinder 41. This gives a protracted discharge of a positive character. In Fig. 3 I have shown a plunger

24' in which the discharge is secured substantially by displacement of liquid by the plunger itself, and the piston 42 and cylinder 41 form essentially a dash-pot construction for preventing successive operations from discharging too much fuel into the carburetor. In Fig. 5 the feature of permitting a by-pass to be opened for a predetermined time, corresponding to the extent of change of opening of the throttle valve, is emphasized.

While in the embodiments shown in Figs. 1 and 3, the plunger 38 is mechanically actuated by the throttle shaft 1, or the means which operates the throttle shaft 7, it is to be understood that this plunger may be operated by other means which will secure depression of the plunger in accordance with opening of the throttle valve. In Fig. 4 I have shown a carburetor in which the plunger 38 is depressed by a spring which is held under compression by the suction existing in the intake manifold. In this construction the guide 46 is extended upwardly, as indicated at 58, to form a cylinder in which a piston 61 is adapted to move. A compression spring 62 is disposed within the piston 61 and it bears against the head 63 of the cylinder 66, tending to depress the piston 61 at all times. The piston 61 is connected to the plunger 38 by a connection or link 64. The cylinder 66 has a series of openings 65 opening to the interior of the float chamber 8 above the liquid level. The space above the liquid level in each form shown herein communicates by way of a vent with atmosphere, although this feature may be varied without departing from my invention. Descent of plunger 61 tends to increase the air pressure on liquid in chamber 8. This may be utilized to assist in feeding additional fuel for acceleration.

A passageway 67 is formed through the head of the cylinder 66, and this communicates through a passageway 68 with a suction port 69 opening into the main passageway of the carburetor above the throttle valve 6, so that the cylinder 66 is subjected to the suction prevailing in the intake passageway above the throttle valve 6.

The plunger 38 has the chamber 41 forming a cylinder for the piston 42. The piston 42 has the hollow stem 24 passing down through an opening in the bottom wall, indicated at 22, this opening being normally closed by the valve 23 which forms the head of the plunger or rod 24. The piston 42 contains the stop pin 45 forming the compensating control, as in the previous embodiment. The hollow rod 24 has the discharge port 44 adapted to be plunged down into the chamber 21 and to discharge its accelerating charge through the controlling restriction 26 in the branch passageway leading to the main passageway 18.

The operation of the device shown in Fig. 4 is substantially the same as that shown in Fig. 1, with the exception that the plunger 38 is actuated by the spring 62 acting under the control of suction in the intake manifold above the throttle. When the throttle is substantially closed the suction in the intake manifold above the throttle is a maximum and the piston 61 will be drawn up against the head 63 of the cylinder 66. The idling charge is drawn through the vertical passageway 26, air for the same passing in 71 through the openings 38 and 39. When the throttle is opened the suction in the intake manifold above the throttle will be reduced, and the spring 62 expands driving the plunger 38 downwardly and discharging a part of the contents 76

of chamber 41, as described in connection with Fig. 1.

To secure best results the spring 62 must be proportioned to assume a definite position for a definite suction in the intake manifold. That is to say, the spring pressure should vary as the same is expanded or collapsed, so as to assume a definite position corresponding to a definite suction. This proportioning of the spring to make it take a corresponding set for a given suction may be accomplished in any well known manner, as by forming it of variable cross section or variable diameter of coil, or by introducing a series of springs of different lengths.

15 The construction of the stem 24 and valve 23 may be identical with that shown in Fig. 1, or it may be as shown in Fig. 3, Fig. 5 or Fig. 6, depending upon the characteristics desired.

In Fig. 6 I have shown a modified form of 20 device for providing the accelerating discharge. According to this construction a cylinder 70, communicating at top and bottom with the float chamber 8, is provided. The communication 71 at the upper end is preferably above the liquid 25 level, and the communication 54 at the lower end is below the liquid level, preferably adjacent the bottom of the float chamber 8. A movable piston 72 fits closely within the cylinder 70. This piston is mounted to slide on the stem 73, which stem 30 at its lower end is drilled to provide a longitudinal passageway communicating laterally at 75 with the interior of the cylinder 70. The stem 73 has a shoulder or collar 76 below the port 75, and the spring 46' which engages at its upper end a collar 77 on the plunger 73 tends to push the piston 72 down over the valve opening 75 to close the same, the collar 76 tending to limit further movement of the piston 72 on said stem. The stem 73 extends up to a pivot joint at 78 where it is connected to the operating arm 38. The spring 47 tends to raise the plunger 73 until the collar 77 engages the cover member 9. When the collar 77 is in engagement with the cover 9, the lower end of the rod 73 projects into and closes the port 45 22, which port is an opening between the cylinder 70 and the chamber 21. The chamber 21 has the restricted outlet, as indicated at 20. The parts are shown in Fig. 6 as though the plunger 73 had just been depressed a short distance to permit 50 the opening 75 to be exposed under the piston 72. The spring 46' has been compressed thereby and it tends to recoil and force the piston 72 downward, forcing liquid therefrom, a part of the liquid being expelled through the passageway 54, 55 and another part through the opening 75 into the passageway 74 in the hollow stem and down into the chamber 21 and through the restriction 20. The passageway 54 in the present instance may be provided with a check valve 79 if so 60 desired.

The stem 73 is provided with a reduced portion at 80 which is adapted to enter the port 22 when the throttle is in substantially wide open position for providing the compensating feed heretofore 65 referred to.

In the present structure, that is, Fig. 6, opening of the throttle is accompanied by depression of the stem 73 and compression of the spring 46' which, upon recoil, forces fuel through the hollow 70 stem until the piston 72 overtakes the port 75 which it over-runs. This prevents further passage of fuel through this auxiliary by-pass including the restriction 20, except upon substantially wide open throttle position where the clearance between the stem 73 and the port 22 per-

mits liquid to be drawn through the passageway 54, the clearance in the passageway 22, through the chamber 21, restriction 20, and into the air flow.

This form of feeding device may be introduced 5 in the form shown in Fig. 4 if so desired. Thus, Figure 8 represents a carburetor embodying the fuel feeding device of Figure 6, vacuum actuated after the manner of the device shown in Figure 4, and having a separate outlet into the mixing 10 chamber, as in Figure 3.

The carburetor shown in Figure 7 is formed merely by substituting, in Figure 3, the acceleration pump actuating means shown in Figure 4, and requires no detailed explanation. The reference numerals applied to the various elements in this figure are the same as those used in Figures 3 and 4.

It will be observed that the accelerating device of my invention provides, first, a displacement 20 effect of liquid useful in providing an accelerating discharge. The plunger 39 in being projected down into the liquid displaces a part of the same and tends to increase the level which assists in a discharge of a greater amount of fuel immediately upon opening the throttle. Likewise, the projection of the stem 24, or 24' or 56, displaces liquid in the chamber 21, also tending to supply additional fuel upon opening of the throttle.

A second effect which is produced by the device 30 of my invention is the syringe effect of the chamber 41 discharging liquid down through the hollow stem and discharge port 44 when the rod or stem 24 is plunged into the chamber 21. This provides a protracted charge, that is, a discharge which 35 occurs after the motion causing it initially has ceased. This spreads the accelerating fuel charge over an appreciable period of time and secures a new and highly beneficial mode of operation.

A further effect is that of opening a by-pass 40 around the normal fuel restriction 19 during the period of acceleration. That is to say, when the throttle valve 6 is further opened from any given position, the valve 23 is opened and, where clearance is provided around the same, fuel may be drawn through said clearance during the time that is required for the spring 46 to close the valve 23. This amounts to a time interval during 45 which a by-pass is opened upon movement of the 50 throttle to a further open position.

In addition to the above effects, a further effect is the compensating effect which is secured by opening the valve 23 by engagement of the plunger 39 with the pins 45 when the throttle is moved 55 in proximity to its wide open position.

I do not intend to be limited to the details shown or described, since the illustration is substantially diagrammatic. My invention provides certain new functions and I intend to claim 60 broadly the means for securing the same.

I claim:—

1. In combination in a carburetor, an air passage, a fuel supply chamber, a fuel supply passage from the chamber to the air passage adapted to 65 convey fuel drawn into the stream of air flowing in said air passage, a throttle for said air passage, a second fuel supply passage for delivering fuel from the fuel chamber into said air passage, 70 a valve normally closing said second passage for preventing the drawing of fuel therethrough, means for jointly opening the throttle and said valve, means for closing the valve, said closing means having a delayed action, and means for 75

- positively holding the valve open when the throttle is wide open.
2. In a carburetor having a main air passage, a fuel supply chamber, a fuel supply passage from the chamber having an outlet into the air passage, a fuel pump having a cylinder adapted to be filled from the fuel chamber and having a discharge passage communicating with the fuel supply passage, said cylinder having a piston fitting therein, a spring for actuating the piston to cause a discharge of fuel from the cylinder into said fuel supply passage, means to compress said spring, and a valve controlling the discharge of the pump and opened upon compression of the said spring. 5
3. In a carburetor, the combination of an air passage having a throttle, a fuel supply chamber, a fuel supply passage from the chamber into the air passage, a second fuel supply passage subject to suction by the air flow in the air passage, a valve normally closing off said latter passage to prevent fuel from being drawn through the same, means operated upon opening movement of the throttle independently of suction to open said valve, a definite time consuming means to close said valve independently of the throttle, said time consuming means comprising a spring actuated piston, and a discharge passage for conveying fuel displaced by said spring actuated piston into 10 said second fuel supply passage. 15
4. In a carburetor, the combination of an air passage having a throttle, a fuel supply chamber, a fuel supply passage from the chamber into the air passage, a second fuel supply passage subject to suction by the air flow in the air passage, a valve normally closing off said latter passage to prevent fuel from being drawn through the same, means operated upon opening movement of the throttle to open said valve, a definite time consuming means to close said valve independently of the throttle, said time consuming means comprising a spring actuated piston, a discharge passage for conveying fuel displaced by said spring actuated piston into said second fuel supply passage, and means to hold said valve open when said throttle is wide open. 20
5. In a carburetor, the combination of an air passage having a throttle, a fuel supply chamber, a fuel supply passage from the chamber into the air passage, a second fuel supply passage subject to suction by the air flow in the air passage, a valve normally closing off said latter passage to prevent fuel from being drawn through the same, means operated upon opening movement of the throttle to open said valve, a definite time consuming means to close said valve independently of the movement of the throttle, and means to hold said valve open when said throttle is wide open. 25
6. In a carburetor, the combination of an air passage having a throttle, a fuel supply chamber, a fuel supply passage from the chamber, an accelerating pump adapted to be filled from the fuel supply chamber and to discharge its fuel into the air passage, actuating means for moving said pump as a whole, and means energized by movement of the pump as a whole for discharging a predetermined quantity of liquid from the pump in accordance with the extent of operation of said actuating means. 30
7. In combination with a throttle controlled carburetor, an accelerating pump device comprising a piston member and a cylinder member movable downward as a whole by opening of the throttle, a pair of springs, one connected to the piston member and the other to the cylinder member, and both energized by downward movement of the pump, a valve controlled by one of said members and opened by downward movement of the pump, the recoil of one of said springs causing movement of the members toward each other to discharge fuel and finally closing the valve, the recoil of the other spring separating the members to draw fuel into the pump. 35
8. In a carburetor, a main air passage having a constriction, a throttle for said passage, a fuel supply chamber having an outlet, a fuel supply outlet orifice for controlling the flow of fuel from said supply chamber, a fuel pump having a cylinder adapted to be filled from the fuel chamber and having a discharge port, a piston for the cylinder, a spring for actuating the piston to cause a discharge of liquid from the cylinder, means to compress the spring upon opening of the throttle, means for conducting the discharge of fuel from the orifice and from the discharge port of the fuel pump into the constriction in the main air passageway, and a valve normally closing the discharge port of the pump while the carburetor is delivering mixture. 40
9. In a carburetor having an air passageway, a Venturi constriction therein, a throttle therefor, means for feeding fuel into the stream of air in the Venturi constriction comprising a fuel supply chamber, a regulable outlet orifice and a delivery passageway leading from said orifice into said venturi and terminating in a delivery orifice therein subjected to the suction in said venturi, and means for providing accelerating fuel to be supplied to the air stream upon sudden opening of the throttle comprising a branch passageway from the fuel supply chamber to said delivery passageway, said branch passageway comprising a valve port, a movable valve member controlling said port, a spring for moving said valve to closed position and normally holding the same closed, and means for moving said valve member to open said port upon opening of the throttle, said means including a liquid dash pot, the liquid discharged from said dash pot passing through said valve port. 45
10. In combination with a throttle controlled carburetor, accelerating means comprising a collapsible chamber adapted to be filled with liquid fuel, said chamber having two ends, a member movable in one direction with the throttle connected to one end of the chamber, a spring pressing against the other end of the chamber, a stem limiting the expansion of the spring, and a valve controlling the discharge of the accelerating means, said valve being opened upon compression of the spring, the recoil of the spring slowly collapsing the chamber to discharge fuel therefrom, and thereafter closing said valve. 50
11. The combination with a throttle controlled carburetor, and means for operating the throttle, of accelerating means comprising a piston member and a cylinder member, a connection from the throttle operating means to one of said members, a valve carried by the other of said members, an accelerating fuel feed passage controlled by said valve, and a spring connected to the other of said members tending to move it toward the said one member and tending also to close said valve. 55
12. In combination with a throttle controlled carburetor and means for operating the throttle, of accelerating means comprising a collapsible chamber consisting of a piston member and a 60
- 75

cooperating cylinder member mounted to have joint motion and individual relative motion, a valve port for accelerating fuel supply, and a valve member controlling said port and being connected to one of said members and movable therewith, a spring for holding the said valve closed and forming a resilient abutment for the said one member, and a connection from the throttle operating means to the other member whereby upon opening movement of the throttle the two members are jointly moved to energize the spring and open the said valve member, the recoil of the spring causing a protracted relative motion of the one member with respect to the other and a closing of said valve member.

13. In combination with a throttle controlled carburetor having a throttle operating means, of an accelerating device comprising a collapsible chamber consisting of two elements, a valve for controlling accelerating fuel feed connected to one of the elements, a spring also connected to said one element, and an impositive connection formed in part by said collapsible chamber between said throttle operating means and said valve, said valve being opened and said spring energized by movement of said throttle operating means to open the throttle, and said valve being closed by the recoil of said spring, the closing of said valve being then delayed by the delayed escape of the contents of said collapsible chamber.

14. In combination with a throttle controlled carburetor having throttle operating means, of an accelerating device comprising a collapsible chamber consisting of a piston and a cylinder, a swinging lever adapted to be actuated in one direction by the throttle operating means, and a spring for actuating it in the other direction, a link connecting the cylinder and the lever, a hollow stem for conveying the discharge of the chamber to the carburetor, a valve controlling said discharge, and a spring energized by movement of the chamber for moving the piston and closing said valve, whereby a protracted discharge is secured from said chamber.

15. In combination with a throttle controlled carburetor having throttle operating means, an accelerating fuel supply passageway having a controlling valve, a spring for closing the same, a collapsible chamber forming a connection between the throttle operating means and the valve for opening the valve and compressing the spring, said chamber collapsing under the pressure of the spring and permitting the valve to close, and means acting when the throttle approaches wide open position for permitting a continuous discharge through said accelerating fuel passage.

16. In a carburetor, a fuel supply chamber, an air passage, a throttle controlling the air passage, a fuel discharge passageway from the chamber leading into the air passage, an accelerating pump taking fuel from the chamber and discharging the same into the air passage, said pump being mechanically actuated upon opening the throttle to displace a definite volume of fuel therefrom in proportion to the opening of the throttle, and an automatic valve for the pump for closing off the discharge thereof when the definite volume corresponding to the setting of the throttle has been displaced from the pump, said pump comprising two members movable relative to each other to displace fuel from between them, one of said members being moved in consonance with throttle movements and the other being connected to the valve.

17. In a carburetor: the combination of a main

air passageway; a fuel supply chamber; a fuel discharge passageway from the chamber to the air passageway, said fuel discharge passageway including a fuel flow constriction governing the normal rate of fuel flow into the air passageway; a by-pass for fuel from the chamber into the air passageway around said fuel flow constriction, said by-pass including a cylinder, a piston projecting into said cylinder, and a plunger carried by the piston and provided with a fuel passage; a throttle for the air passageway; means for operating said throttle; and a connection from the throttle operating means to said piston including said cylinder.

18. In a carburetor, the combination of an air passage having a throttle, means for operating said throttle, a fuel supply chamber, a fuel supply passage from the chamber into the air passage, a second fuel supply passage subject to suction by the air flow in the air passage, means to operate the throttle, a cylinder member, a piston member therefor, a spring for moving one of said members with respect to the other to force liquid from between them, means including said members for compressing said spring, an operative connection between said throttle operating means and said spring compressing means, and a spring for restoring said members to normal position after operation.

19. In a carburetor, the combination of an air passage having a throttle, a fuel supply chamber, a fuel supply passage from the chamber into the air passage, a second fuel supply passage subject to suction by the air flow in the air passage, a valve normally closing off said second passage to prevent fuel from being drawn therethrough, means to operate the throttle, a cylinder member, a piston member therefor, a spring for moving one of said members with respect to the other to force liquid from between them, means including the cylinder and piston for compressing said spring and opening said valve, an operative connection between said throttle operating means and said spring compressing means, and a spring for restoring said members to normal position after operation.

20. In a throttle controlled carburetor having a venturi, a fuel supply chamber, a nozzle opening into the venturi and connecting with said fuel supply chamber, a collapsible syringe device connecting with the fuel supply chamber, said syringe being actuated by opening of the throttle for ejecting fuel, a separate passageway leading from said syringe device to said venturi, and a valve for automatically cutting off connection between said device and said passageway after the syringe is collapsed.

21. In a carburetor having a throttle, a fuel nozzle, and means for supplying fuel thereto; an economizer valve for controlling the flow of additional fuel to the nozzle, an acceleration device, and an intermediate member actuated in one direction by the opening movement only of said throttle and actuated in the opposite directions by a spring, said member in turn actuating the economizer valve and the acceleration device.

22. In a carburetor having a throttle, an acceleration device comprising two members arranged to pump fuel by movement of either member relative to the other, one of said members being resiliently mounted and the other moved when the throttle is opened.

23. In a carburetor having a throttle, an acceleration pump comprising a fuel container having two relatively movable walls, one of which is

- yieldable under pressure, the other of which is so connected as to be moved toward said one wall when the throttle is opened.
24. In a carburetor having a throttle, an acceleration device comprising a fuel container having walls relatively movable to vary the capacity of the container, means for moving one of said walls in accordance with the position of the throttle, another of said walls being yieldable in response to pressure within the chamber developed by movement of said one wall.
25. A charge forming device for internal combustion engines comprising, a mixture passage adapted to supply a combustible mixture to the intake port of the engine, means for supplying fuel and air thereto, a throttle controlling the flow through the mixture passage, means within the mixture passage for increasing the velocity of flow therethrough and means for supplying additional fuel to said mixture passage at the point where the velocity of flow is increased, whereby said additional fuel is more readily atomized.
26. A charge forming device for internal combustion engines comprising, a mixture passage adapted to supply a combustible mixture to the intake port of the engine, means for supplying fuel and air thereto, a throttle controlling the flow through the mixture passage, means within the mixture passage for increasing the velocity of flow therethrough, means for supplying additional fuel to said mixture passage at the point where the velocity of flow is increased, and means for rendering said last mentioned means effective on opening movements of the throttle.
27. A charge forming device for internal combustion engines comprising, a mixture passage adapted to supply a combustible mixture to the intake port of the engine, means for supplying fuel and air thereto, a throttle controlling the flow through the mixture passage, a Venturi tube in the mixture passage for increasing the velocity of flow therethrough, and means for supplying additional fuel to said mixture passage within the Venturi tube on opening movements of the throttle.
28. The combination with a throttle-controlled carburetor comprising a mixing chamber, of an accelerating device comprising a cylinder and a plunger operating therein, means for supplying fuel to said cylinder, a fuel delivery passage from said cylinder to the mixing chamber, means for actuating a pressure stroke of said plunger concurrently with the opening of the throttle and for simultaneously connecting said fuel supply means and delivery passage, and means for automatically effecting a retarded closing of said discharge passage upon completion of throttle-opening movement.
29. The combination with a throttle-controlled carburetor comprising a mixing chamber, of an accelerating device, comprising a fuel pump discharging into said mixing chamber, means actuated in common with said throttle upon its opening travel for actuating said pump, to deliver a charge of fuel therefrom to the mixing chamber and for establishing a subsequent abnormal fuel flow to the mixing chamber responsive to reduced pressure in said chamber, and means effective in the open position of the throttle for gradually and automatically cutting off such flow.
30. The combination with a throttle-controlled carburetor including a mixing chamber and means comprising a normal fuel supply for said mixing chamber, means for increasing the fuel supply during certain operating conditions, and mechanisms for operating the last named means in conjunction with the throttle, said operating mechanism including a dash pot for varying the effectiveness of said last named means to increase the flow of fuel according to the rapidity of operation of said operating mechanism.
31. The combination with a throttle-controlled carburetor comprising a mixing chamber, of an accelerating device comprising a fuel pump discharging into the mixing chamber, a valve controlling the discharge from said pump, means actuated by said throttle in its opening travel for actuating said pump to force a charge of fuel into the mixing chamber and for opening said valve to establish a subsequent flow responsive to reduced pressure in the mixing chamber, and means effective in the open position of the throttle for gradually and automatically closing said valve.
32. The combination with a throttle-controlled carburetor comprising a mixing chamber, of an accelerating device comprising a fuel pump having a discharge connection to the mixing chamber, a valve controlling such connection and means variably responsive to movements of the throttle according to the rapidity of operation of the latter for actuating said pump and valve from the throttle.
33. The combination with a throttle-controlled carburetor comprising a mixing chamber, of a fuel-pump having a discharge connection to said mixing chamber, means for supplying fuel to said pump, and an actuating connection from said throttle to said pump, said actuating connection being variably responsive to actuation of the throttle according to the carburetor temperature.
34. The combination with a throttle-controlled carburetor comprising a mixing chamber, and means establishing a normal fuel supply to said chamber, of means for increasing such supply, and an actuating connection to the last named means from the throttle, varying in its effective response to control in an inverse proportion to the temperature, under which the control is exercised.
35. The combination with a throttle-controlled carburetor comprising a mixing chamber, of an accelerating device comprising a fuel pump having a discharge connection to said mixing chamber and a dash-pot forming an actuating connection to said pump from said throttle, effective to vary the response of said pump to a throttle movement, according to the rapidity of such movement.
36. The combination with a throttle-controlled carburetor comprising a mixing chamber, of an accelerating device comprising a fuel pump having a discharge connection to the mixing chamber, a valve controlling such connection, a dash-pot operable by the throttle upon its opening movement to effect a pressure stroke of said pump and an unseating of said valve, said dash-pot being variably responsive to said throttle according to the rapidity of throttle movement, and means for effecting a retarded seating of said valve.
37. The combination with a throttle-controlled carburetor comprising a mixing chamber, of a fuel pump having a discharge connection to said mixing chamber, means for supplying fuel to said pump, a dash-pot operatively connecting said pump and throttle, effective to vary the response of said pump according to the rapidity of actuation of said throttle, and spring means estab-

lishing the normal position of said pump and dash-pot.

38. The combination with a throttle-controlled carburetor comprising a mixing chamber, of a dash-pot comprising a piston and cylinder, means for actuating one of said dash-pot parts in common with the throttle, a spring opposing movement of the other dash-pot part responsive to throttle actuation; a pump comprising a cylinder and plunger, one of which is operatively connected to the freely movable dash-pot part, a fuel delivery passage from said pump to said mixing chamber, means for supplying fuel to said pump and means normally closing said fuel supply adapted to be opened by a throttle-responsive actuation of the dash-pot.

39. In a carburetor, comprising a mixing chamber and a throttle, means establishing a normal fuel delivery to said mixing chamber, a fuel pump for temporarily delivering additional fuel to the mixing chamber, and an actuating connection from the throttle to said pump including a common means to render said connection unresponsive to gradual throttle movement and to retard the suction stroke of the pump.

40. In a carburetor, means forming a mixing conduit, a throttle valve controlling said mixing conduit, normal fuel supply means for said mixing conduit, auxiliary fuel supply means for said mixing conduit, means for operating said auxiliary fuel supply means in response to opening movements of said throttle, and a suction operated device for cutting off said auxiliary fuel supply means.

41. In a carburetor, means forming a mixing conduit, an accelerating pump for supplying fuel to said mixing conduit and a suction operated device for cutting off the flow of fuel from said accelerating pump.

42. In a carburetor, an air system including a venturi, a fuel system for delivering fuel thereto and including a plurality of nozzles terminating within said venturi, means effective for normally delivering fuel through part only of said nozzles, vacuum operated pump means effective for delivering an accelerating charge through another of said nozzles, and valve means controlled by said pump means and effective after delivery of the accelerating charge to continue the delivery of an enriching charge through said last mentioned nozzle.

43. In a carburetor including a fuel reservoir and having an air passage, a normal fuel system for feeding fuel into said air passage, a pick-up system including a pump and having an auxiliary fuel passage communicating with said air passage independently of said normal fuel system and with said pump, said fuel passage being subject to the suction in the air passage, and a check valve controlling said fuel passage so arranged that suction in the air passage tends to close the valve, said valve being adapted to prevent discharging of fuel from said fuel passage and pump when the latter is inoperative.

44. In a carburetor having a fuel mixture passage including a throttle valve, a main fuel system for supplying fuel to said fuel mixture passage, a fuel reservoir, means for temporarily feeding a charge of fuel into said fuel mixture passage including a pump and an auxiliary passageway having an outlet communicating with said fuel mixture passage at an elevation above that of the fuel level in said reservoir, said auxiliary passageway being subject to the suction in the fuel mixture passage, the main portion of said

auxiliary passageway being normally filled with fuel by the head of fuel in said reservoir, and a check valve in said auxiliary passageway located below the fuel level in said reservoir for sealing said auxiliary passageway against the vacuum in said fuel mixture passage and so arranged that suction in the fuel mixture passage tends to close said valve.

45. In a carburetor, an air system including a venturi, a nozzle system for delivering normal fuel supply to said venturi, a supplemental nozzle system for delivering an enriching charge to said venturi, said supplemental nozzle system including an operative connection to a source of fuel supply and containing both a check valve and an economizer valve normally so positioned as to prevent the supply of fuel through the supplemental nozzle system, and means for first closing the check valve and then opening the economizer valve for delivering an accelerating charge through said supplemental nozzle system and thereafter establishing an enriching flow through said supplemental nozzle system from said source of supply.

46. In a carburetor, an air system, a nozzle system for normally delivering fuel to the air system, a supplemental nozzle system having a flow passage including both a normally closed economizer valve and normally open check valve, and fluid pressure operated means for opening said economizer valve and temporarily closing said check valve.

47. In a carburetor, an air system and a float chamber, a nozzle system for delivering normal fuel supply to said air system from said float chamber, and including a connection with said float chamber, a supplemental nozzle system for delivering an enriching charge to said air system and including a second separate connection to said float chamber, said second connection containing both a check valve and an economizer valve normally so positioned as to prevent the supply of fuel through the supplemental nozzle system, and means for first closing the check valve and then opening the economizer valve for delivering an accelerating charge through said supplemental nozzle system without disturbing the fuel flow through said first mentioned nozzle system, and thereafter establishing an enriching flow through said supplemental nozzle system from said float chamber.

48. In a carburetor, an air system and a float chamber, a nozzle system for delivering normal fuel supply to said air system from said float chamber, and including a connection with said float chamber, a supplemental nozzle system for delivering an enriching charge to said air system and including a second separate connection to said float chamber, said second connection containing both a check valve and an economizer valve normally so positioned as to prevent the supply of fuel through the supplemental nozzle system, and vacuum operated pump means for first closing the check valve and then opening the economizer valve for delivering an accelerating charge through said supplemental nozzle system without disturbing the fuel flow through said first mentioned nozzle system, and thereafter establishing an enriching flow through said supplemental nozzle system from said float chamber.

49. In a carburetor having a main air passage, a fuel supply chamber, a fuel supply passage from the chamber having an outlet into the air passage, a fuel pump having a stationary

- 5 cylinder adapted to be filled from the fuel chamber and having a discharge passage communicating with the fuel supply passage, said cylinder having a piston fitting therein, a spring for actuating the piston to cause a discharge of fuel from the cylinder into said fuel supply passage, and a valve controlling the discharge of the pump and including the piston.
- 10 50. In combination with a throttle controlled carburetor having means for operating the throttle, of accelerating means comprising a piston and a cylinder, a yielding connection from the throttle operating means to the piston, and an accelerating fuel feed passage leading from the cylinder and controlled by said piston.
- 15 51. In a carburetor, an acceleration pump comprising a cylinder adapted to receive fuel, a throttle actuated member movable longitudinally of the cylinder, a piston slidable on said member, and an outlet formed in said member and controlled by the position of the piston.
- 20 52. In a carburetor having a fuel passage, an acceleration pump comprising a chamber adapted to receive fuel, a throttle actuated member movable longitudinally of the chamber, a piston slidable on said member and yieldingly urged in one direction thereon, and an outlet duct formed in said member having one of its ends normally obstructed by the piston and its other end discharging into said fuel passage.
- 25 53. In a carburetor having a fuel mixture passage, a fuel reservoir, a pick-up system including a pump having a fuel inlet communicating with said reservoir and an outlet passage communicating with said fuel mixture passage, a check valve in said fuel inlet, and means controlling said outlet passage for sealing the latter against the vacuum in said fuel mixture passage when said pump is inoperative.
- 30 54. In a carburetor having a fuel mixture passage including a throttle valve, a fuel reservoir, means for temporarily feeding a charge of fuel into said fuel mixture passage including a pump and having a fuel passageway communicating with said fuel mixture passage, the main portion of said fuel passageway being normally filled with fuel by the head of fuel in said reservoir, a valve in said passageway normally preventing the flow of fuel therethrough under the influence of the suction in said fuel mixture passage when said pump is inoperative, means associated with said valve for moving the same to an open position by the pressure of the fuel in said passageway when said pump is actuated, and yielding means for closing said valve when the pressure of the fuel in said passageway falls below a predetermined value.
- 35 55. In a carburetor having a fuel mixture passage including a throttle valve, a fuel reservoir, means for temporarily feeding a charge of fuel into said fuel mixture passage including a pump and having a fuel passageway communicating with said fuel mixture passage, the main portion of said fuel passageway being normally filled with fuel by the head of fuel in said reservoir, a valve in said passageway normally preventing the flow of fuel therethrough under the influence of the suction in said fuel mixture passage when said pump is inoperative, means associated with said valve for moving the same to an open position by the pressure of the fuel in said passageway when said pump is actuated, yielding means tending to close said valve, and mechanism operable upon opening movement of said throttle for actuating
- 40 56. In a carburetor having a throttle and a fuel reservoir, an acceleration device comprising a fuel chamber communicating with the reservoir, an actuating member positively moved when the throttle is opened, fuel-displacing means in the chamber slidably related to said actuating member, resilient means engaging the actuating member and the fuel-displacing means to yieldingly resist sliding movement therebetween under the influence of fuel pressure when the device is actuated, and a check valve preventing flow of fuel from the chamber to the reservoir.
- 45 57. In a carburetor having a throttle and a fuel reservoir, an acceleration device comprising a fuel chamber having a restricted connection to the fuel reservoir, an actuating member movable in consonance with throttle position, a fuel-displacing member in said chamber slidably related to the actuating member, and resilient means transmitting the force of the actuating member to the fuel-displacing member.
- 50 58. In a carburetor having a throttle, actuating mechanism therefor, and a fuel reservoir, an acceleration pump comprising an actuating member connected to the throttle actuating mechanism to be positively moved when the throttle is opened, a fuel chamber having a restricted connection to the reservoir, fuel-displacing means in the chamber slidably related to the actuating member, and resilient means transmitting the movement of the actuating member to the fuel-displacing member.
- 55 59. In a carburetor having a throttle, actuating mechanism therefor, and a fuel reservoir, an acceleration device comprising an actuating member movable in accordance with throttle position, a fuel chamber receiving fuel from the reservoir, a piston in the chamber slidable on the actuating member, a connection between the actuating member and the piston including resilient means designed to transmit force from the actuating member to the piston, and means operative at least during the working stroke of the piston to restrict the flow of fuel from the chamber to the reservoir.
- 60 60. In a carburetor having a throttle and a fuel reservoir, an acceleration device comprising an actuating member movable in accordance with throttle position, a fuel chamber supplied with fuel from the reservoir, a fuel-displacing member in the chamber, a sliding connection between the actuating member and the fuel-displacing member including resilient means for transmitting force from the actuating member to the fuel-displacing member, and a pressure-responsive fuel inlet valve controlling the flow of fuel between said chamber and said reservoir.
- 65 61. In a carburetor, a throttle valve, an actuating member movable with and by the throttle valve, a pump to supply additional fuel to the mixture when the throttle valve is opened and including an independently movable element, and also including a positively operated prime acting member movable with respect to said movable element and a yieldable connecting member between said movable pump element and said prime acting member, and means to positively actuate the prime acting member and hence cause the yieldable member to impart continuous pumping stroke to the movable member during a limited period of time, said means being operated by said actuating member which is movable with and by the throttle valve.
- 70 62. In a carburetor having a fuel mixture passage, a throttle valve for controlling the flow of

fuel mixture from said passage, means for regulating said throttle valve, a pick-up mechanism including a pump cylinder having an outlet communicating with said fuel mixture passage, a piston in said cylinder, a plunger extending in advance of and movable relative to said piston having a stem actuated positively by said throttle valve regulating means for discharging fuel into said mixing chamber simultaneously with the opening of said throttle, and resilient means coating between said stem and said piston yieldably urging the latter toward said plunger for supplementing the discharge of fuel during opening of said throttle valve and for continuing the discharge of fuel from said cylinder for a limited period after said throttle valve is opened.

63. In a carburetor having a fuel mixture passage, a throttle valve for controlling the flow of fuel mixture from said passage, apparatus for regulating said throttle valve, a pick-up mechanism including a cylinder having an outlet communicating with said fuel mixture passage, means actuated positively by said throttle valve regulating apparatus for discharging fuel into said fuel mixture passage simultaneously with the opening of said throttle, a piston in said cylinder, and a yieldable member bearing between said positive acting fuel discharging means and said piston for imparting a delayed fuel discharging action to the latter.

64. In a carburetor having a fuel mixture passage, a throttle valve for controlling the flow of fuel mixture from said passage, apparatus for regulating said throttle valve, a pick-up mechanism including a cylinder having an outlet communicating with said fuel mixture passage, a plunger slidably mounted in said cylinder occupying substantially less than the full cross-sectional area thereof and having a stem actu-

ated positively by said throttle regulating apparatus, a piston slidably mounted on said stem located between said plunger and the outer end of said cylinder and having an outer periphery closely fitting the inner periphery wall of said cylinder, an abutment on said stem, and a spring bearing between said piston and said abutment normally urging said piston toward said plunger.

65. In a carburetor, pick-up mechanism including a cylinder, a pair of relatively movable fuel-displacing members slidably mounted in said cylinder, one of said members being in close fitting relation with the inner periphery of said cylinder and the other member occupying less than the full cross-sectional area of said cylinder, means for positively operating the latter fuel-displacing member including rigid actuating elements, and resilient means bearing between said rigid elements and the close fitting fuel-displacing member for operating the latter.

66. In a carburetor having a fuel mixture passage, a throttle valve in said passage, apparatus for regulating said valve, pick-up pump mechanism including a pump cylinder, a pair of relatively movable fuel-displacing members in said cylinder, one being in close fitting relation with the inner peripheral walls of said cylinder and the other occupying less than the full cross-sectional area of said cylinder, rigid actuating elements connected with said throttle valve regulating means for positively actuating the latter member simultaneously with the opening of said throttle valve, and a yieldable actuating element coating between said rigid elements and the close fitting fuel-displacing member for imparting a delayed action thereto during opening of said throttle valve.

DISCLAIMER

2,141,594.—*Don Cole*, Chicago, Ill. CARBURETOR. Patent dated December 27, 1938. Disclaimer filed October 18, 1939, by the assignee, *Bendix Products Corporation*.

Hereby enters this disclaimer to claims 33, 34, 40, and 41 of said patent.
[Official Gazette November 7, 1939.]

fuel mixture from said passage, means for regulating said throttle valve, a pick-up mechanism including a pump cylinder having an outlet communicating with said fuel mixture passage, a piston in said cylinder, a plunger extending in advance of and movable relative to said piston having a stem actuated positively by said throttle valve regulating means for discharging fuel into said mixing chamber simultaneously with the opening of said throttle, and resilient means coating between said stem and said piston yieldably urging the latter toward said plunger for supplementing the discharge of fuel during opening of said throttle valve and for continuing the discharge of fuel from said cylinder for a limited period after said throttle valve is opened.

63. In a carburetor having a fuel mixture passage, a throttle valve for controlling the flow of fuel mixture from said passage, apparatus for regulating said throttle valve, a pick-up mechanism including a cylinder having an outlet communicating with said fuel mixture passage, means actuated positively by said throttle valve regulating apparatus for discharging fuel into said fuel mixture passage simultaneously with the opening of said throttle, a piston in said cylinder, and a yieldable member bearing between said positive acting fuel discharging means and said piston for imparting a delayed fuel discharging action to the latter.

64. In a carburetor having a fuel mixture passage, a throttle valve for controlling the flow of fuel mixture from said passage, apparatus for regulating said throttle valve, a pick-up mechanism including a cylinder having an outlet communicating with said fuel mixture passage, a plunger slidably mounted in said cylinder occupying substantially less than the full cross-sectional area thereof and having a stem actu-

ated positively by said throttle regulating apparatus, a piston slidably mounted on said stem located between said plunger and the outer end of said cylinder and having an outer periphery closely fitting the inner periphery wall of said cylinder, an abutment on said stem, and a spring bearing between said piston and said abutment normally urging said piston toward said plunger.

65. In a carburetor, pick-up mechanism including a cylinder, a pair of relatively movable fuel-displacing members slidably mounted in said cylinder, one of said members being in close fitting relation with the inner periphery of said cylinder and the other member occupying less than the full cross-sectional area of said cylinder, means for positively operating the latter fuel-displacing member including rigid actuating elements, and resilient means bearing between said rigid elements and the close fitting fuel-displacing member for operating the latter.

66. In a carburetor having a fuel mixture passage, a throttle valve in said passage, apparatus for regulating said valve, pick-up pump mechanism including a pump cylinder, a pair of relatively movable fuel-displacing members in said cylinder, one being in close fitting relation with the inner peripheral walls of said cylinder and the other occupying less than the full cross-sectional area of said cylinder, rigid actuating elements connected with said throttle valve regulating means for positively actuating the latter member simultaneously with the opening of said throttle valve, and a yieldable actuating element coating between said rigid elements and the close fitting fuel-displacing member for imparting a delayed action thereto during opening of said throttle valve.
